UNITED STATES PATENT OFFICE.

ARTHUR CIRONS SMITH, OF COLORADO SPRINGS, COLORADO, ASSIGNEE OF ONE-HALF
TO WILLIAM WALTER HASSELL, OF COLORADO SPRINGS, COLORADO.

COMBINED ATOMIZER AND VAPORIZER FOR OIL ENGINES.

Application filed March 5, 1921. Serial No. 449,940.

To all whom it may concern:

Be it known that I, ARTHUR CIRONS SMITH, a citizen of the United States, and a resident of Colorado Springs, in the county of El Paso and State of Colorado, have invented certain new and useful Improvements in Combined Atomizers and Vaporizers for Oil Engines, of which the following is a specification.

10 My invention relates to combined atomizers and vaporizers adapted for use in conjunction with oil engines, and it contemplates certain new and useful improvements over the atomizer and vaporizer embodied in 15 my co-pending application Serial No. 395,709, filed July 12, 1920.

The purpose of my present invention is the provision of a combined atomizer and vaporizer including atomizing and vaporizing members one of which is movably associated with the other to occupy positions wherein the atomized oil is injected either into the vaporized member or directly into the cylinder of the engine, so that when 25 starting the engine or when the latter is running under a light load, the vaporizing member is employed to effect a thorough vaporization of the fuel, while on the other hand when the engine is heated sufficiently to effect the flashing of oil as it is introduced 30 into the cylinder or when the engine is running under a heavy load, the oil can be ejected directly into the cylinder and without contacting with the vaporizer.

35 I will describe one form of combined atomizer and vaporizer embodying my invention and one form of oil engine to which it is adapted to be applied, and will then point out the novel features thereof in 40 claims.

In the accompanying drawings:

Figure 1 is a view showing partly in longitudinal section a conventional form of oil engine having applied thereto one form of 45 combined atomizer and vaporizer embodying my invention.

Figure 2 is an enlarged fragmentary sectional view of the vaporizing member in its applied position within the engine.

50 Figure 3 is a transverse sectional view taken on the line 3-3 of Figure 1.

Figure 4 is a transverse sectional view taken on the line 4-4 of Figure 2.

55 Figure 5 is an enlarged detail view showing in longitudinal section the atomizing

member shown in Figure 1 and in operative relation to the confronting end of the vaporizing member.

Figures 6 and 7 are sectional views taken on the lines 6-6 and 7-7 of Figures 5 and 60 1, respectively.

Figure 8 is an enlarged detail perspective view of the nozzle comprised in the atomizing member shown in Figure 5.

Similar reference characters refer to similar parts in each of the several views.

Referring specifically to the drawings and particularly to Figures 1 and 7, the combined atomizer and vaporizer forming the subject matter of my present invention essentially consists of an atomizing member A and a vaporizing member V both of which are adapted to be removably associated with the explosive end of any conventional form of oil engine. As shown in Figure 5, the atomizing member A in the present instance comprises an elongated body 15 formed with a longitudinally extending duct 15^a which communicates at one end with an oil supply pipe 16, the latter in turn being connected 70 to an oil injection pump (not shown) of any standard form. The opposite end of the duct 15^a communicates with a chamber 15^b, the outer end portion of which is of increased diameter with its wall threaded to receive a nozzle 17. As shown in Figures 5 and 8, the nozzle 17 consists of a round body 75 formed at one end with an annular flange 17^a carrying a pin 17^b which is adapted to seat within a suitable recess formed in the body 15 for locking the nozzle as a unit against rotation. As shown in Figure 5, the nozzle is formed with a diagonally extending duct 17^c which communicates at one end with a V-shaped recess 17^d in such manner 80 that any liquid traversing the duct will impinge upon one inclined wall of the recess so as to be deflected laterally from the nozzle. In the applied position of the nozzle within the chamber 15^b, the flange 17^a abuts the shoulder formed between the wide and narrow portions of the chamber with the pin 17^b locking the nozzle against rotation. The nozzle is confined within the chamber 85 by means of a collar 18 which threadedly engages the inner wall of the chamber in the manner shown and abuts the flange 17^a so that the nozzle is locked against outward movement. The inner end of the nozzle is provided with a stud 17^e which functions to 90

95 100 105 110

that any liquid traversing the duct will impinge upon one inclined wall of the recess so as to be deflected laterally from the nozzle. In the applied position of the nozzle within the chamber 15^b, the flange 17^a abuts the shoulder formed between the wide and narrow portions of the chamber with the pin 17^b locking the nozzle against rotation. The nozzle is confined within the chamber 85 by means of a collar 18 which threadedly engages the inner wall of the chamber in the manner shown and abuts the flange 17^a so that the nozzle is locked against outward movement. The inner end of the nozzle is provided with a stud 17^e which functions to 90

position a coiled expandible spring 19 that engages a ball valve 20 for normally closing the adjacent end of the duct 15^a.

As shown in Figures 1, 2 and 7, the vaporizing member V comprises a tube 21 formed with a slot 21^a which is co-extensive in length with the tube. Within the tube at opposite sides of the slot 21^a two series of perforations 21^b are formed, with the perforations of each series arranged at regular spaced intervals throughout the length of the tube. Permanently secured within one end of the tube 21 is a head 22 provided with a stem 23 which is rotatably fitted within a screw plug 24. The outer end of the plug 24 is provided with a transverse slot 24^a as clearly shown in Figure 3 and into this slot is adapted to removably fit a locking lip 25^a formed on a handle 25 which is fixed to the stem 23 by a pin 26.

In Figure 1, I have illustrated a conventional form of oil engine, the cylinder head of which is provided at diametrically opposite points with suitable openings for the reception of the atomizing and vaporizing members. In the applied position of these members to the cylinder head, the vaporizing member V is inserted into the largest opening of the cylinder head so that it extends almost entirely across the door of the cylinder. In this applied position the tube 21 rotatably fits within the cylinder opening, with the plug 24 threadedly engaging the walls of the opening in the manner clearly shown in Figure 2. Adjacent this cylinder opening, the walls of the cylinder are provided with recesses 27 into which is adapted to fit a locking key 28 for locking the handle 25 against rotation in one direction. The atomizing member A is threadedly fitted within the other opening of the cylinder head, a nut 17^f being formed at the outer end of the body 15 to facilitate the application or removal of the atomizing member to or from the cylinder head. As applied, the nozzle 17 is partly inserted into the adjacent end of the tube 21 of the vaporizing member in the manner clearly shown in Figures 2 and 5. With the atomizing and vaporizing members so assembled, it will be clear that the slots 21^a of the tube 21 can be moved into or out of registration with the recess 17^a of the nozzle 17 by manual manipulation of the handle 25. In order to effect this adjustment, the handle 25 is pulled outwardly from the cylinder so as to remove the locking lip 25^a from the slot 24^a, and by removing the key 28 from the cylinder, it will be clear that the handle 25 can now be rotated and by such rotation the tube 21 can be moved to cause the slot 21^a to aline or disaline with respect to the recess 17^a. The tube can be locked in either of these positions by re-applying the key 28 to that recess 27 disposed adjacent one of the arms of the handle

25 so as to lock the handle against rotation in one direction.

In operation, the vaporizing member is initially heated before insertion into the cylinder whereupon oil under pressure is supplied to the atomizing member A through the pipe 16. As the oil leaves the pipe 16 it enters the duct 15^a and because of its pressure opens the valve 20 where it traverses the chamber 15^b and enters the nozzle 17^c through the duct 17^e. As the oil leaves the duct 17^c it impinges upon the inclined wall of the recess 17^d where it is atomized and deflected laterally toward the tube 21. When the tube 21 is in the position shown in the drawings the atomized oil is ejected directly to the cylinder through the slot 21^a. However, when the tube is rotated by means of the handle 25 so that the recess 17^d is disaligned with respect to the slot 21^a, the atomized oil impinges upon the inner side of the tube where it is vaporized before entering the cylinder. The tube 21 is adjusted to cause the atomized oil to impinge upon its inner side when starting the engine or when the engine is working under a light load. However, when the engine is working under a heavy load and the introduction of large quantities of oil into the cylinder is necessary, the tube is rotated to allow of the oil being projected directly into the cylinder. It will be manifest that the movement of the tube 21 to either of its two positions can be effected while the engine is in operation so that should the load be changed from a light to a heavy, or vice versa, the tube can be adjusted accordingly to provide for this change in load, and without the necessity of stopping the engine.

Although I have herein shown and described only one form of combined atomizer and vaporizer embodying my invention, it will be understood that various changes and modifications may be made herein without departing from the spirit of the invention or the spirit and scope of the appended claims.

What I claim is:

1. A vaporizing member comprising, an elongated slotted member, and means adapted to rotatably support the member within the head of a cylinder.

2. In combination, an engine cylinder, an atomizing member extending into the cylinder for injecting atomized fuel into the cylinder, and a vaporizing member comprising, a slotted element rotatably supported within the cylinder to occupy one position in which the fuel from the atomizing member is injected interiorly of the slotted member and another position in which the fuel passes through the slot of the slotted member and into direct contact with the walls of the cylinder.

3. In combination, an engine cylinder, an atomizing member extending into the cyl-

- inder for injecting atomized fuel into the cylinder, and a vaporizing member comprising, a slotted element rotatably supported within the cylinder to occupy one position in which the fuel from the atomizing member is injected interiorly of the slotted member, and another position in which the fuel passes through the slot of the slotted member and into direct contact with the walls of the cylinder, and means operable from a point exteriorly of the cylinder for moving the vaporizing member to either of its positions.
4. In combination, an engine cylinder, an atomizing member extending into the cylinder for injecting atomized fuel into the cylinder, and a vaporizing member comprising, a slotted element rotatably supported within the cylinder to occupy one position in which the fuel from the atomizing member is injected interiorly of the slotted member, and another position in which the fuel passes through the slot of the slotted member and into direct contact with the walls of the cylinder, means operable from a point exteriorly of the cylinder for moving the vaporizing member to either of its positions, and means for locking the vaporizing member in either of its positions.
5. An atomizing member comprising, a body having a duct formed therein and a chamber communicating with the duct, a nozzle within the chamber, a flange formed on the inner end of the nozzle, a pin engageable with the flange and with said body for locking the nozzle against rotation within the chamber, a collar threadedly fitted within the body and engageable with said flange for locking the nozzle against displacement, a recess formed in the nozzle, a duct formed in the nozzle and establishing communication between the chamber and said recess, and a spring pressed valve within the chamber and controlling the adjacent end of the body duct.
6. A vaporizing member comprising, a tubular element formed longitudinally with a co-extensive slot and perforations in the element adjacent the slot, a head fixed within one end of the element, a stem formed on said head, an actuating handle fixed to said stem, a plug rotatably and slidably fitted on said stem, and coacting means formed on the plug and handle for locking the stem against rotation with respect to the plug.
7. In combination, an engine cylinder having the cylinder head thereof formed with an opening, and a vaporizing member comprising, a slotted tubular element rotatably mounted in the opening and extending into the cylinder, a head fixed within one end of the element, a plug removably fitted within the opening of the cylinder head, a stem formed on said head and rotatably and slidably fitted within said plug, a handle sustained on the stem, and co-acting means formed on the plug and handle for locking the handle against rotation.
8. In combination, an engine cylinder having the cylinder head thereof formed with an opening, and a vaporizing member comprising a slotted tubular element rotatably mounted in the opening and extending into the cylinder, a head fixed within one end of the element, a plug removably fitted within the opening of the cylinder head, a stem formed on said head and rotatably and slidably fitted within said plug, a handle sustained on the stem, and co-acting means formed on the plug and handle for locking the handle against rotation, recesses formed in the cylinder head, and a locking key insertable in said recesses and engageable with said handle for the purpose described.
9. In combination, an engine cylinder having the cylinder head thereof formed with openings at diametrically opposite points, an atomizing member extending into the head through one of the openings, and a vaporizing member extending into the heads through the other of the openings, said vaporizing member comprising a screw plug fitted within the corresponding opening, a stem rotatably and slidably fitted in said plug, a slotted tubular element sustained on the stem and receiving one end of the atomizing member, and an actuating handle rigidly attached to said stem and disposed exteriorly of the cylinder for actuating the tubular element.
10. In combination, an engine cylinder having openings formed therein at diametrically opposite points, atomizing members extending into the cylinder through one of the openings, and a vaporizing member extending into the cylinder through the other opening, said vaporizing member including a screw plug fitted within the corresponding opening and having a slot formed in the outer end thereof, a stem rotatably and slidably fitted in the screw plug, a head formed on the inner end of the stem and adapted to engage said plug to provide an air-tight joint between the cylinder and the plug, a slotted tubular element sustained on the head and receiving the inner end of the atomizing member, an actuating handle on the outer end of the stem, a lip carried by said handle and adapted to fit in said slot for the purpose described.

ARTHUR CIRONS SMITH.
